[57] CLAIM

The ornamental design of a handle for a bait casting fishing rod, as shown and described.

DESCRIPTION

FIG. 1 is a top plan view of my new handle for a bait casting fishing rod;

FIG. 2 is a right-side elevational view thereof;

FIG. 3 is a bottom plan view thereof;

FIG. 4 is a front elevational view thereof;

FIG. 5 is a rear elevational view thereof;

FIG. 6 is a top plan view of another embodiment of FIG. 1;

FIG. 7 is a right-side elevational view thereof;

FIG. 8 is a bottom plan view thereof;

FIG. 9 is a front elevational view thereof; and

FIG. 10 is a rear elevational view thereof.

The left-side elevational view of the embodiment of FIGS. 1-5 is a mirror image of the right elevational view shown in FIG. 2.

The left elevational view of the embodiment of FIGS. 6-10 is a mirror image of the right-side elevational view shown in FIG. 7.
